US0D1067033S

(12) **United States Design Patent** (10) **Patent No.:** **US D1,067,033 S**
(45) **Date of Patent:** **** Mar. 18, 2025**

(54) **PACKAGING FOR DRINKING POWDER**

(71) Applicant: **Daily Doctor (Shanghai) Trading Co., Ltd.**, Shanghai (CN)

(72) Inventor: **Yuxuan Tang**, Shenzhen (CN)

(73) Assignee: **DAILY DOCTOR (SHANGHAI) TRADING CO., LTD.**, Shanghai (CN)

(**) Term: **15 Years**

(21) Appl. No.: **29/970,052**

(22) Filed: **Oct. 25, 2024**

(51) **LOC (15) Cl.** **09-03**

(52) **U.S. Cl.**

USPC **D9/428; D7/400**

(57) **CLAIM**

The ornamental design for a packaging for drinking powder as shown and described.

DESCRIPTION

The application file contains at least one drawing executed in color. Copies of this patent or patent application publication with color drawing(s) will be provided by the Office upon request and payment of the necessary fee.

FIG. 1 is a perspective view of a packaging for drinking powder showing the new design;

FIG. 2 is a front view thereof;

FIG. 3 is a back view thereof;

FIG. 4 is a left side elevational view thereof;

FIG. 5 is a right side elevational view thereof;

FIG. 6 is a top view thereof; and,

FIG. 7 is a bottom view thereof.

1 Claim, 7 Drawing Sheets
(7 of 7 Drawing Sheet(s) Filed in Color)
